(57) **CLAIM**

The ornamental design for a shallow recessed lighting fixture, as shown and described.

DESCRIPTION

FIG. 1 is a perspective view of the shallow recessed lighting fixture, showing my design;

FIG. 2 is an enlarged right side elevational view;

FIG. 3 is an enlarged left side elevational view;

FIG. 4 is a top plan view;

FIG. 5 is a bottom plan view;

FIG. 6 is a front elevational view; and,

FIG. 7 is a rear elevational view.

The broken lines in the drawings represent unclaimed portions of the shallow recessed lighting fixture.
